4 Claims. (Cl. 330—18)

This invention relates to a series feed type transistor amplifier and more particularly to a temperature compensation circuit of such a series feed type transistor amplifier.

One object of this invention is to provide a temperature compensation circuit of a series feed type transistor amplifier which is simple in connection and effective in operation.

Another object of this invention is to provide a temperature compensation circuit of a series feed type transistor amplifier in which a comparatively minor number of circuit elements can be used with easy adjustment and stable operation.

A further object of this invention is to provide a temperature compensation circuit of a series feed type transistor amplifier in which only one temperature compensation element is connected to either one transistor circuit of two transistor circuits connected in parallel so that all the transistors are prevented from being affected by the temperature variation.

A still further object of this invention is to provide a single ended push-pull transistor amplifier output circuit in which a pair of transistors are connected in series to each other and signals are supplied respectively to them to be amplified in the push-pull type and a load is connected to the connecting point of the two transistors.

Other objects, features and advantages of this invention will become more apparent from the following description taken in conjunction with the accompanying drawing in which,

The single figure is a circuit diagram illustrating an embodiment of a temperature compensation circuit of a series feed type transistor amplifier according to this invention.

Referring now to the drawing, an example of the temperature compensating circuit of this invention will hereinafter be explained. 1 is a signal source and 2 shows a direct current power source. To the both ends of this direct current power source 2 is connected a series circuit of transistors 3a and 3b of the same conductivity type, for example PNP type which are connected in series to each other. That is, a series circuit of an emitter resistor 4a—the emitter electrode of the transistor 3a—the collector electrode thereof—an emitter resistor 4b—the emitter electrode of the transistor 3b—the collector electrode thereof is connected to the both ends of the power source 2. To the output side of the signal source 1 is connected the primary coil of a transformer 5 which is provided with a pair of secondary coils 5a and 5b. A series circuit of voltage dividing resistors 6a and 7a is connected to the power source 2 and their connecting point 8a is connected to the base of the transistor 3a through the secondary coil 5a of the transformer 5. Similarly, a series circuit of voltage dividing resistors 6b and 7b is connected to the power source 2 and their connecting point 8b is connected to the base of the transistor 3b through the secondary coil 5b. Thus, base bias voltages are applied respectively to the transistors 3a and 3b. These circuits are referred to as base bias circuits.

2

Furthermore, signals are respectively supplied across the base and emitter of the transistor 3a and across the base and emitter of the transistor 3b through a capacitor 9 inserted between the connecting point 8b and the connecting point 12 of the collector of the transistor 3a and the emitter resistor 4b. A load 11, for example, a speaker is connected across the connecting point 12 and a reference point through a direct current blocking capacitor 10.

With such a connection of the circuit, a voltage of approximately $\frac{1}{2}$ of the voltage of the power source 2 is applied as an operating voltage to the two transistors 3a and 3b and signals are supplied from the signal source 1 and then they are applied to the load 11 after amplified in the push-pull manner. This kind of the circuit is called a series feed type single ended push-pull output circuit.

In such an output circuit, the transistors 3a and 3b are affected by temperature and so their characteristics may be changed accordingly, and hence it is desired to do the temperature compensation of the transistors 3a and 3b respectively. To accomplish this, it is generally sufficient to connect a temperature compensating element to both of the base bias circuits of the transistors.

However, we paid our attention to the fact that when carrying out the temperature compensation of transistors the variation due to the temperature of one transistor exerts influence on the other transistor because the two transistors are connected in series to each other. That is, we found that by connecting a temperature compensating element, for instance a thermistor 13 to the base bias circuit of one transistor, practical objects could be sufficiently accomplished without respectively connecting temperature compensating elements to the both transistors as in the conventional method.

That is, with the connection of a temperature compensating element to the base bias circuit of one transistor, the temperature compensation of the other transistor can be effected simultaneously. The collector current I_{c2} of the transistor 3b is under control of the collector current I_{c1} of the transistor 3a and the latter I_{c1} is controlled by the base bias voltage of the transistor 3a. Therefore, both the currents I_{c1} and I_{c2} are controlled under the same temperature compensation. Even if the unbalanced ratio, namely, I_{c2}/I_{c1} between the two transistors becomes a little worse by the connection of a temperature compensating element to one transistor circuit alone, its influence on the distortion factor is, in fact, out of the question in almost all cases. In the case where the value of a plurality of the voltage dividing resistors 6b and 7b connected to the base bias circuit of the transistor 3b without having the temperature compensating element connected thereto is increased, power consumption across terminals 14 and 15 can be made sufficiently small. The direct current resistance across terminals 16 and 17 serves as an emitter external resistor with respect to the transistor 3b and stable operation can be expected owing to the feedback effect.

Thus, the temperature compensation of two transistors can be performed simultaneously with one temperature compensating element and the adjustment can be simplified because the number of circuit elements is decreased.

A embodiment of this invention is as follows:

Voltage dividing resistor:

6b	1.2KΩ
7b	0.8KΩ
6a	75Ω
7a	1.2KΩ
Emitter resistors 4a and 4b	18Ω
Capacitor 9 and D.C. suppressing capacitor 10	50μf.
Load 11	75Ω

It will be apparent that many modifications and variations may be effected without departing from the scope of the novel concept of this invention.

What is claimed is:

1. A series energized transistor amplifier comprising
  - (a) a direct current source,
  - (b) a pair of transistors each having a base, an emitter, and a collector electrode,
  - (c) a series circuit including the emitter and collector of each transistor connected across said direct current source,
  - (d) input means including a pair of base bias circuits each connected across said direct current source and each connected to the base electrode of a respective one of said transistors,
  - (e) a load connected between a common connection point of said transistors and one side of said direct current source, and
  - (f) a temperature compensating element connected to only one of said base bias circuits whereby temperature compensation of said transistors can be simultaneously performed.
2. A series energized transistor amplifier as defined in claim 1 wherein each of said base bias circuits includes a voltage dividing circuit and a secondary coil of a trans-

former, each of said voltage dividing circuits includes at least two voltage dividing resistors, one end of one of said secondary coils being connected to the base electrode of one of said transistors and the other end of said one secondary coil being connected through one of said voltage dividing resistors to said direct current source, said temperature compensating element being connected in shunt with said one voltage dividing resistor.

5 3. A series energized transistor amplifier as defined in claim 2 wherein the resistance value of another of said voltage dividing resistors is substantially larger than that of said one voltage dividing resistor.

10 4. A series energized transistor amplifier as defined in claim 2 wherein each of said transistors is of the same conductivity type as the other.
